DISCONNECT SWITCH

Herbert J. Crabbs, Wilkinsburg, Pa., assignor to
Westinghouse Electric & Manufacturing Company, East Pittsburgh, Pa., a corporation of Pennsylvania

Application April 16, 1936, Serial No. 74,708

15 Claims.

(Cl. 200—48)

My invention relates to electrical switching equipment and particularly to high voltage disconnecting switches.

Devices of this type are utilized primarily for interconnecting and for isolating portions of a high voltage transmission or other power distribution system, and in this service are subjected to a number of very exacting operational requirements, some of which are conflicting in nature. In the interest of safety, it is practically imperative that disconnecting switches shall show a visible break in the controlled circuit when in the open position. Ordinarily this means that the devices must be air break switches, and as a result, the switches are subjected to all types of weather conditions. Disconnecting switches are operated but infrequently, yet when called upon they must be capable of opening the controlled circuit despite corrosion, ice or sleet formation, or other conditions. Further, the devices should be automatically capable of cutting through oxidation and corrosion in order to assure low resistance contacts throughout their operative lives. As opposed to these operational requirements, commercially successful disconnecting switches must be relatively low in cost due to the large numbers which are used on even a small transmission system.

The principal object of the present invention, therefore, is to provide a simple, reliable disconnecting switch which shall be capable of satisfactorily meeting the above stated requirements. The particular structure utilized for accomplishing this object of the invention is an improvement and a further refinement of the switch disclosed in my Patents Nos. 2,039,059 and 2,067,659 issued April 28, 1936, and January 12, 1937, respectively. The present device differs from the structures shown in those patents in that it is a side break switch, either of the two insulator or of the three insulator type, and in applying the principles disclosed in the above-mentioned patents to a side break switch I accomplish another of the objects of my invention.

The present invention, as do the structures disclosed in the above cited patents, utilizes a parallel blade construction. One of the blades is a unitary member which is provided with a toothed portion for engaging a similar toothed portion forming a part of the stationary contact means in order to permit the mechanical interconnecting of the rotatable insulator and the stationary contact means and the other blade member comprises an articulated blade element, one end of which is connected to the rotatable

insulator and the other end of which is connected to the unitary blade member adjacent the unsupported end thereof. During the operation of the switch, the unitary blade element is swung into engagement with the stationary contact. By this operation the cooperating toothed members are caused to engage each other, thereby mechanically interconnecting the rotatable insulator and the stationary insulator. A lost motion connection intermediate the unitary blade and the rotatable insulator allows the further rotation of that insulator, which rotation causes the articulated blade element to be moved longitudinally and at the same time laterally with respect to the unitary blade element. The combined result of this longitudinal and lateral movement is to provide a high pressure wiping engagement between the cooperating portions of the blade elements and the contact means.

A further object of the present invention is to generally simplify the structure of switches of this type by reducing the number of parts required to the minimum and to increase the reliability in operation of the structures.

Other objects will be apparent in the following description of the two preferred embodiments of the invention. Referring to the drawings,

Figure 1 is a side elevational view of a three insulator side break disconnecting switch utilizing the features of the present invention.

Fig. 2 is a plan view of the structure shown in Fig. 1.

Fig. 3 is an enlarged fragmentary plan view similar to Fig. 2, showing the switch in the partially open position.

Fig. 4 is a fragmentary elevational view similar to Fig. 1, showing the relative position of the blade elements and the cooperating stationary contact when the switch is in the partially open position.

Fig. 5 is a fragmentary sectional view showing the details of the lost motion connection between the unitary blade element and the rotating insulator.

Fig. 6 is a fragmentary sectional view showing the details of the cooperating contact portions of the stationary contact means and the blade elements, the switch being in the fully closed position.

Fig. 7 is a side elevational view similar to Fig. 1 of a two insulator side break switch embodying the features in the present invention.

Fig. 8 is a plan view of the switch shown in Fig. 7; and

Fig. 9 is a sectional view taken on the line IX—IX of Fig. 7.

The three insulator switch illustrated in Figs. 1 through 6, inclusive, includes a base 1 which is 5 preferably formed from a piece of channel iron, a pair of stationary insulators 2 mounted on said base through the use of a pair of suitable spacers 3, and a rotatable insulator 4 mounted on the base intermediate the two stationary insulators. 10 A ball bearing connection 5 permits the rotatable insulator 4 to be moved freely with respect to the base. A stationary contact assemblage 7 is supported upon each of the stationary insulator columns 2 and a blade means 8 movable into and out 15 of engagement with these contact means is supported upon the rotatable insulator 4.

Each of the stationary contact assemblages 7 includes a jaw member 9 which is cast integral with the base portion 10 of the assemblage and 20 an outwardly projecting portion 11 which is utilized as one of the terminals for the switch. The upper of the two inner surfaces of each of the jaw members 9 is machined into a knife edge form as shown at 13 in Fig. 6 for cooperating 25 with one of the toothed portions 14 of the blade assemblage 8 and the lower surface of each of the jaw contacts is machined so as to define a curved surface as shown at 15 for cooperating with one of the contact portions 16 of the blade assemblage. The outer portion of each of the jaw contacts is flared in order to facilitate the entry 30 of the cooperating blade portions therein.

The blade assemblage 8 comprises in effect one 35 unitary blade member 17 which is supported on the rotatable insulator 4 for swingable movement about the axis thereof and a pair of articulated blade elements 18, likewise supported upon the rotatable insulator 4 but which are movable independently of the unitary blade element 17 during 40 the operation of the switch in order to effect high contact pressure between the cooperating contact portions of the blade means and the contact jaws and to effect the operation of the means for mechanically interconnecting the spaced stationary insulator columns. The unitary blade element 17 includes a pair of tubular blade members 19, each of which is rigidly affixed to a centrally positioned cap member 21 which is bolted to the support member 22 for the 45 blade assemblage, which member is, in turn, bolted to the cap 23 of the rotatable insulator 4. The cap member 21 is movable with respect to the support member 22 through a definitely restricted distance and a coil spring 24 is provided for biasing the cap member 21 and the blade portions supported thereon to a predetermined position with respect to the support member. The toothed portion 14 for engaging the toothed portion 13 of the cooperating contact jaw is brazed 50 or otherwise rigidly affixed to the other end of each of these tubular blade members 19.

As is shown particularly in Figs. 1 and 4, the support member 22 for the blade assemblage is provided with a pair of outwardly projecting 55 crank arms 25 and the inner end of each of the other two tubular blade members 19 is pivotally affixed to each of these crank members, the resultant structure comprising a pair of articulated blade elements. The contact element 18, substantially similar to the toothed members 14 except that the lower surface thereof is flat, is affixed to the outer end of each of the blade elements 19, and the unsupported end of each of the articulated blade elements 18 is mechanically 60 connected to the adjacent unsupported end of 75

the unitary blade element 17 by a pair of tie links 27, one end of each of these links being pivotally joined to one of the members by suitable pivot pins.

It will thus be seen that the blade assemblage 5 comprises in effect one substantially rigid blade element which is provided with toothed portions for engaging the toothed portions of both of the two contact jaws and a pair of articulated blade elements fastened at their inner end to the rotatable insulator column and fastened at their outer end by suitable tie links to the unitary blade structure. The spring 24 intermediate the rotatable support member 22 and the cap member 21 biases the several portions of the blade assemblage to the position shown in Fig. 4. That is, it biases the articulated blade elements 18 to a position where the contact portions 16 thereof are as closely adjacent the toothed portions 14 of the unitary blade structure as is possible. This 20 facilitates the engagement of the cooperating portions of the blade means and the contact jaws during the operation of the switch.

The switch is shown in the fully closed position in Fig. 1. In this position, the toothed contact 25 portions 14 of the unitary blade element 17 and the plain contact portions 16 of the articulated blade elements 18 are held into intimate engagement with the cooperating portions of the contact jaws 9. The rather considerable length 30 of the blade elements 18 and the positioning of the link members 27 closely adjacent the outer end of the blade assemblage allows the inherent resilience of the blade members to be utilized as the source of contact pressure between the cooperating portions of the blade assemblage and the contact jaws. To open the switch, the rotatable insulator 4 is turned in a clockwise direction (Fig. 2) from the position shown in Fig. 1 to the position shown in Fig. 4. This clockwise 40 rotation actuates each of the articulated blade members 18 through the crank arms 25 joined thereto, and moves each of the blade members longitudinally with respect to the unitary blade element 17. The presence of the links 27 causes 45 the contact portion 16 to move in the direction of the toothed portion 14 and thus decreases the space between those portions so as to permit easy disengagement of the portions from the contact jaw 9. The swivel connection between the cap member 21 and the support member 22 allows this longitudinal and lateral movement of the contact portions 16 to take place without moving the unitary blade structure 17. When the articulated blade elements 18 have reached the position 50 shown in Fig. 4, or the limit of their relative movement with respect to the blade members 19, further rotation of the rotatable insulator 4 in the clockwise direction will cause the toothed members 14 to disengage the cooperating toothed portions 13 of the contact jaw 9 as shown in Fig. 3, and the entire blade assemblage to move to the position shown by the dotted lines in Fig. 2, the normal fully open position of the switch.

To close the switch, the central insulator 4 is 65 rotated in a counter-clockwise direction so as to swing the blade assemblage from the open circuit position to a position where the toothed portions 14 of the unitary blade element 17 engage the cooperating portions 13 of the contact 70 jaws. The biasing spring 24 causes the blade assemblage to remain in the position shown in Fig. 4 during this portion of closing operation. As soon as the toothed portions 14 engage the closed end of the jaws 9, further rotation of the unitary 75

blade element 17 is prevented and a subsequent rotation of the central insulator 4 will cause the articulated blade portions 18 to be moved from the position shown in Fig. 4 to the position shown in Fig. 1. This movement of the articulated blade elements 18 causes each of the blade portions 18 thereof to be moved longitudinally and laterally with respect to the unitary blade element 17, and the combined result of this longitudinal and lateral movement is to produce a high pressure wiping engagement between the cooperating contact surfaces 15 of the contact jaws 9 and the contact portions 16 of the two articulated blade elements. The lateral movement of the articulated blade elements 18 also effects an intimate engagement between the toothed portions 18 of the contact jaws 9 and the toothed portions 14 of the unitary blade element 17, thus assuring that the two spaced stationary insulators 2 shall be rigidly interconnected when the switch is in the fully closed position.

By interconnecting the switches, the spaced stationary insulators 2, during the switch closing operation, are subjected to substantially no cantilever stress. This permits the use of high pressure contacts with a wiping action and in addition makes for a much more rugged structure.

Figs. 7 through 9 illustrate an embodiment of my invention as applied to a two insulator side break switch. The various structural elements of the device are mounted upon a base 30 which, similar to the base 1 of the previously described structure, may be of channel iron and include a stationary insulator column 31 having a stationary contact means 32 supported thereon and a rotatable insulator column 33 supported upon the base 30 by means of a bearing 34. A blade assemblage 35 is supported upon and adapted to be actuated in response to the rotation of the rotatable insulator 33.

The stationary contact assemblage 32 comprises a jaw member 37 which is bolted to the stationary supporting insulator 31; therefor, this jaw being substantially the same as the jaw members 9 in the structure just described, and has a knife edge 18, upper portion and a curved lower portion 15 as is shown in Fig. 6.

The blade assemblage 35 comprises a pair of blade elements 38 and 39. The element 38 is a unitary member and is rigidly affixed at one end to a substantially U-shaped support 40, adapted to engage a bearing pin 41 which projects upwardly from a cast frame 42. The frame 42 is bolted to a cap 44 of the rotatable insulator 33, as is shown particularly in Fig. 7. The outer end of the blade member 38 is provided with a toothed portion 45 for engaging the toothed portion 18 of the cooperating contact jaw 37.

The blade element 39 is somewhat shorter than the element 38 and is supported upon an outwardly projecting crank member 46 cast integral with the frame 42 by means of a pivot pin 47. The other end of the blade member 39 is provided with a contact portion 48 for engaging the cooperating portion 15 of the contact jaw 37 and is mechanically connected to the outer end of the blade element 38 by means of a link or pair of links 50 and two pivot pins 51.

A cylindrical member 52 is journaled upon the shaft portion 41 of the frame 42 and is provided with an outwardly projecting element 53 for supporting one of the terminals of the switch. A flexible shunt 54 connects the cylindrical member 52 with the blade element 38 and this element, in turn, is connected to the blade element

38 by means of a second pair of shunts 55. Through this arrangement the terminal at 53 of the switch is free to turn with respect to the rotatable insulator 33 during the operation of the device. The other terminal of the switch is formed by an outwardly projecting element 57 cast integral with the contact jaw 37.

A coil spring 58 which is positioned intermediate the U-shaped support 40 and the crank portion 46 of the articulated blade element 38 serves to bias the blade assemblage to a position substantially as that shown in Fig. 4; that is, to a position where the contact portion 48 of the articulated blade element 38 has been moved as far as possible in the direction of the toothed portion 45 of the unitary blade element 38. This arrangement, as has been explained in the foregoing, facilitates the entry of the unsupported end of the blade assembly into the cooperating contact jaw 37.

The operation of this embodiment of my invention is substantially the same as the operation of the three insulator switch previously described. The device is shown in the closed circuit position in Fig. 7. To open the switch, the insulator 33 is rotated in a clockwise direction (Fig. 8), thereby causing the articulated blade element 38 to be moved substantially to the position shown in Fig. 4. The coil spring 58 acts to bias the blade element 38 into engagement with the contact jaw 37 during this longitudinal and lateral movement of the contact portion 48 of the blade element 38. As soon as the articulated blade element 38 has reached the position shown in Fig. 4, the rotation of the rotatable insulator 33 is transmitted to the blade element 38 and the entire assemblage is then swung as a unit from the closed circuit position to the open circuit position which may be 90°, more or less, from the position shown in Fig. 8.

The closing operation of the switch is substantially the reverse of the opening operation. The rotatable insulator 33 is turned so as to swing the entire blade assemblage from the open circuit position to a position where the toothed portion 45 of the blade element 38 engages the cooperating toothed portion of the jaw element 37. The biasing spring 58 by holding the blade elements in the position shown in Fig. 4, assures that the contact and toothed portions 48 and 45, respectively, of that assemblage shall be readily moved into the contact jaw 37. Upon further rotation of the rotatable insulator 33 the articulated blade portion 38 is moved from the collapsed to the extended position, thus moving the blade member 38 longitudinally and laterally with respect to the blade element 38, this movement being controlled by the links 50 connecting the plain contact and the toothed contact portions 48 and 45, respectively, of the blade assemblage 35 at their unsupported end. The combined result of this longitudinal and lateral movement is to produce a high pressure wiping engagement of the cooperating contact portions 48 and 15 of the blade 38 and the contact jaw 37 and to cause the cooperating toothed contact portions 45 and 18 of those structures to be forced into intimate engagement with each other.

By utilizing a toothed element having a plurality of separate teeth as the interconnecting means for the insulators 31 and 33, a structure is provided which is capable of automatically adjusting itself to a very substantial amount of relative displacement of the stationary and the rotatable insulators. Satisfactory operation of the

interconnecting means under extremely adverse conditions is thus assured.

From the foregoing it will be seen that I have described two embodiments of a novel form of side break disconnecting switch which possess numerous advantages over the structures heretofore known to the art. More particularly, I have disclosed a double break three insulator disconnecting switch which is provided with means for rigidly interconnecting the three insulators during the operation of the switch so as to impart rigidity and strength to the device, and which interconnecting means is capable of automatically adjusting itself to a very substantial amount of relative displacement of the several insulators of the switch. Further, I have shown how this interconnecting means can be applied to a switch structure which utilizes cooperating contacts adapted to engage each other with a high pressure wiping engagement.

I have also disclosed how the above features for automatically interconnecting the rotating insulator and the spaced stationary insulator may be applied to a two insulator side break disconnecting switch with all of the advantages resulting in the case of the three insulator switch. Both of the structures are relatively simple in design, they are easy to service and are not unreasonably costly.

While in accordance with the patent statutes, I have disclosed in the foregoing the details of certain preferred embodiments of my invention, it is to be understood that many of these details are merely illustrative and variations in their precise form will be both necessary and desirable in certain instances. It is my intention, therefore, that the language of the accompanying claims shall be accorded the broadest reasonable construction and shall be limited only by what is expressly set forth therein and by the prior art.

I claim the following as my invention:

1. In an electric switch, a pair of spaced insulator columns, contact means mounted on each of said spaced insulator columns, a rotatable insulator disposed intermediate said spaced insulator columns, a blade means normally supported on said rotatable insulator for movement into and out of engagement with said contact means, and means responsive to the rotative movement of said rotatable insulator for causing said blade means to engage said contact means with a high pressure contact, said blade means having contact portions adapted to interlock with said contact means in one of a plurality of predetermined positions for interconnecting said spaced insulator columns prior to movement of said blade means into high pressure engagement with said contact means.

2. In an electric switch, a pair of spaced insulator columns, contact means rigidly supported on each of said insulator columns, a rotatable insulator column disposed intermediate said spaced insulator columns, and a blade means normally supported upon said rotatable insulator column and movable, in response to the rotation thereof, into and out of engagement with said contact means, said blade means and said spaced insulator columns having cooperating toothed members for rigidly interconnecting said spaced insulator columns when said interrupter is in the closed circuit position, and said toothed members being disposed longitudinally of said blade means for engagement with each other irrespective of the displacement within certain limits of said

spaced insulator columns to rigidly interconnect said columns without subjecting the columns to substantial cantilever stress.

3. In an electric switch, a pair of spaced insulator columns, contact means rigidly supported upon each of said columns, a rotatable insulator disposed intermediate said spaced columns, a blade means supported on said rotatable insulator having a contact portion at opposite ends thereof movable into and out of engagement with said contact means in response to rotation of said rotatable insulator, and means responsive to the rotative movement of said rotatable insulator for causing said contact portions of said blade means to engage said contact means with a wiping action, said blade means having other contact portions adapted to interlock with said contact means in one of a plurality of predetermined positions for interconnecting said spaced insulator columns prior to movement of said first-named contact portions into wiping engagement with said contact means.

4. In an electric switch, a pair of spaced insulator columns, contact means mounted on each of said insulator columns, a rotatable insulator disposed intermediate said spaced insulator columns, and a blade means supported upon said rotatable insulator and movable into and out of engagement with said contact means in response to the rotation of said rotatable insulator, said blade means including means for rigidly interconnecting said spaced insulator columns during the circuit closing operation, said interconnecting means including cooperating toothed members at least one of which has a plurality of teeth to provide for cooperative engagement of said members in any one of a plurality of positions, a contact portion for engaging each of said contact means, and means for causing each of said contact portions to be moved, with respect to the contact means with which it coacts during each switch closing operation so as to effect a high pressure wiping engagement between each of said contact portions and said contact means.

5. In an electric switch, a pair of spaced insulator columns, contact means rigidly supported upon each of said insulator columns, a rotatable insulator disposed intermediate said spaced insulator columns, and conducting means supported upon said rotatable insulator column and movable into and out of engagement with said contact means, in response to the rotation of said rotatable insulator, said conducting means including a plurality of blade elements, one of which comprises a relatively rigid bridging member supported on said rotatable insulator for swingable movement about the axis of rotation thereof, and the other of said blade elements comprising a blade member, said bridging member and said contact means being provided with cooperating toothed members adapted to engage each other in any one of a plurality of positions for rigidly interconnecting said spaced insulator columns when said interrupter is in the closed circuit position, said blade member including a contact portion which engages each of said contact means, and means for moving said blade member during each closing operation of said switch into a high pressure wiping engagement with said contact means.

6. In a side break electric switch, a stationary contact means, a rotatable insulator and a blade means supported thereon for swingable movement into and out of engagement with said stationary contact means in response to the rota-

tion of said rotatable insulator, said blade means including a unitary blade member supported on said rotatable insulator for relatively rotatable movement about the pivotal axis thereof between predetermined angular positions, an articulated blade member pivotally affixed at one end to said rotatable insulator, a linkage joining the other end of said articulated blade member to said unitary blade member adjacent the unsupported end thereof, and means operable in response to the rotation of said rotatable insulator between said predetermined angular positions for moving said articulated blade member longitudinally and independently of said unitary blade member, said linkage being responsive to the longitudinal movement of said articulated blade member for effecting a high pressure wiping engagement between the cooperating contact portions of said contact means and said blade members.

7. In a side break electric switch, a stationary contact means, a rotatable insulator and a blade means supported thereon for swingable movement into and out of engagement with said stationary contact means in response to the rotation of said rotatable insulator, said blade means including a unitary blade member supported on said rotatable insulator for relatively rotatable movement about the pivotal axis thereof between predetermined angular positions, an articulated blade member pivotally affixed at one end to said insulator, a linkage joining the other end of said articulated blade member to said unitary blade member adjacent the unsupported end thereof, and means operable in response to the rotation of said rotatable insulator between the predetermined angular positions for moving said articulated blade member longitudinally and independently of said unitary blade member, said linkage being responsive to the longitudinal movement of said articulated blade member for effecting a high pressure wiping engagement between the cooperating contact portions of said contact means and said articulated blade member, the contact portions of said unitary blade member and the cooperating contact portion of said contact means being provided with serrated surfaces for positively interlocking said unitary blade member with said contact means in any one of a plurality of positions.

8. In an electric switch, a stationary insulator column, a contact means mounted thereon, a rotatable insulator, a blade means comprising a pair of blade elements supported upon said rotatable insulator and swingable into and out of engagement with said contact means in response to the rotation thereof, one of said blade elements being rotatably supported upon said rotatable insulator for relative rotative movement about the pivot of said insulator, a mechanical linkage connecting the other of said blade elements at its outer end to said first mentioned blade member, a crank member rigidly affixed to said rotatable insulator and pivotally connected to the inner end of said other blade element, said support means for said first-named blade element permitting the rotation of said crank member independently of said first-named blade element during the final stages of each closing operation of said switch, said last-mentioned blade element being movable longitudinally with respect to said first-mentioned blade element in response to the rotation of said crank during the circuit closing operation, said mechanical linkage being actuatable in response to the longitu-

dinal movement of said blade member for causing the contact portion of at least one of said blade elements to engage the cooperating contact portion of said contact means with a high pressure wiping engagement.

9. In an electric switch, a stationary insulator column, a contact means mounted thereon, a rotatable insulator, means comprising a pair of blade elements supported upon said rotatable insulator and swingable in response to the rotation thereof into and out of engagement with said contact means, lost motion means operatively coupling one of said elements and said rotatable insulator, the other of said blade elements being mechanically connected at its outer end to said first-mentioned blade element and pivotally connected at its inner end to a crank member rigidly affixed to said rotatable insulator, said first-mentioned blade element and said contact means having cooperating toothed portions adapted to engage each other in any one of a plurality of positions for positively interconnecting said stationary insulator column and said rotatable insulator column when said interrupter is in the closed circuit position, said last-mentioned blade element being movable longitudinally with respect to said first-mentioned blade element in response to movement of said crank member rigidly affixed to said rotatable insulator column to cause a high pressure wiping engagement between the cooperating contact portions of said contact means and said blade means and to effect the cooperative engagement of said interconnecting means during each operation of said switch.

10. An electric switch including a contact, a rotatable actuating insulator, a switch blade having a contact at one end thereof for engaging the first said contact, said switch blade being pivotally mounted on said rotatable insulator and being actuated thereby, the pivot of the switch blade being coincident with the axis of rotation of the insulator and permitting rotation of the insulator relative to the blade, spring means between the blade and the insulator tending to maintain them in a predetermined angular position with respect to one another, said rotatable insulator being rotatable relative to said blade against the bias of said spring after engagement of the contacts to move the contacts into final high pressure engagement, and the engageable surfaces of said contacts having cooperating toothed portions for positively interlocking the switch blade with said first contact in any one of a plurality of positions as determined by the displacement between said first contact and said insulator.

11. In an electric switch, a contact member, a pair of switch blades each having a contact at one end thereof for engaging said contact member, a linkage joining said blades adjacent said contacts, a rotatable insulator for pivotally supporting said switch blades and for actuating them to open and closed positions, one of said switch blades being rotatably movable with respect to said insulator between predetermined angular positions, and means responsive to the rotation of said insulator between said predetermined angular positions for moving the other of said switch blades longitudinally with respect to said first blade, said linkage being responsive to the longitudinal movement of said switch blade for causing said contacts to firmly engage said contact member, at least one of said switch blade contacts and the cooperating contact portion of said contact member being provided with

serrated surfaces for positively interconnecting the switch blade and contact member.

12. In an electric switch, a supporting insulator, a contact member mounted on said insulator, 5 a rotatable insulator, a pair of blade members mounted upon said rotatable insulator and operable by the rotation thereof into engagement with said contact member, a linkage joining said blade members adjacent the end which engages said contact member, said rotatable insulator being rotatable relative to one of said blade members between predetermined angular positions, the other of said blade members being longitudinally movable with respect to the first said 10 blade member by the rotative movement of said rotatable insulator between said predetermined angular positions to actuate said linkage and thereby move said blade members into final high pressure contact with said contact member, and 15 the engageable contact surfaces of at least one of said blade members and said contact member having cooperating toothed portions for positively interconnecting said insulators when the 20 switch is in the closed position.
13. In an electric switch, a contact member, a pair of switch blades each having a contact at one end thereof for engaging said contact member, a linkage joining said blades adjacent said contacts, a rotatable insulator for pivotally supporting said switch blades and for actuating them to open and to closed positions, one of said switch blades being rotatably movable with respect to said insulator between predetermined angular positions, means biasing said first-named 25 blade to a predetermined angular position with respect to said insulator, and means responsive to the rotation of said insulator between said predetermined angular positions against said biasing means for moving the other of said switch blades longitudinally with respect to said first blade, said linkage being responsive to the longitudinal movement of said switch blade for 30 causing said contacts to firmly engage said contact member, at least one of said switch blade contacts and the cooperating contact portions of said contact member being provided with serrated surfaces for positively interconnecting the 35 switch blade and contact member. 5
14. In an electric switch, a supporting insulator, a contact member mounted on said insulator, a rotatable insulator, blade means carried by said rotatable insulator adapted to be swung 10 into and out of engagement with said contact member by rotation of said rotatable insulator, and means responsive to the rotative movement of said rotatable insulator for causing said blade means to engage said contact member with a 15 high pressure contact, said blade means having contact portions adapted to interlock with said contact member in one of a plurality of predetermined positions for interconnecting said support and said rotatable insulators prior to movement of said blade means into high pressure engagement with said contact member. 20
15. In an electric switch, a pair of spaced insulator columns, one of which is rotatable, a contact member supported upon the other insulator 25 column, a pair of blade elements carried by said rotatable insulator column, said blade elements being adapted to be moved into and out of engagement with said contact member in response to rotation of said rotatable insulator column, 30 and means responsive to the rotation of said rotatable insulator column for moving said blade elements into final high pressure engagement with said contact member, at least one of said blade elements and said contact member having 35 a serrated contact portion for interlocking engagement with each other in one of a plurality of positions prior to movement of said blade elements into final high pressure engagement with said contact member. 40

HERBERT J. CRABBS.
